UNITED STATES PATENT OFFICE.

ARTHUR M. CHAMBERS, OF SHEFFIELD, COUNTY OF YORK, ENGLAND.

COKE-OVEN.

SPECIFICATION forming part of Letters Patent No. 286,983, dated January 25, 1881.

Application filed April 19, 1880. (No model.) Patented in England December 15, 1879.

To all whom it may concern:

Be it known that I, ARTHUR MARSHALL CHAMBERS, of Sheffield, in the county of York, England, have invented a new and useful Improvement in Coke-Ovens, (which was patented to me in England, December 15, 1879, said patent being numbered 5,122,) which improvement is fully set forth in the following specification and accompanying drawings, in which—

10 Figure 1 is a longitudinal section of a coke-oven with part of an adjoining oven, showing my improvement. Fig. 2 is a front view, and Fig. 3 is a horizontal section, of the same.

The object of my invention is to furnish a device by which air is admitted to the interior of the oven above the burning coal, and directed to the flue leading to the chimney, so that the combustion of gas from the coal can be exactly regulated as desired, and the state 20 of the interior of the oven can be watched at any time by an attendant, or its temperature tested by a pyrometer.

In the drawings, *a* is the body of the oven. (Shown dome or bee-hive shaped.) *b* is an 25 opening or doorway, through which the coal is introduced and the coke withdrawn, this opening being built up during the process of burning.

c is a small opening at the crown of the 30 oven, having a loose cover, *d*. *e* is another opening, opposite the doorway *b*, and communicating through the flue *f* with a chimney.

g is a pipe, of cast-iron or other suitable material, surrounding the crown of the oven, close 35 to the fire-brick lining of the latter. This pipe is covered with non-conducting material, and has one of its ends brought to the front of the oven, and provided with a regulating-valve at *h*, while its other end is brought 40 round to the front of the oven, above the doorway *b*, where it is turned upward and inward for a short distance, its open end *i* being directed exactly to the center of the opening *e*.

In a line with and entering the open end of 45 the pipe *i* is a small pipe, *l*, through which the state of the interior of the oven can be observed, or a pyrometer introduced for the purpose of ascertaining its temperature. The outer end of the pipe *i* can be closed with a 50 plug or cap.

The oven being filled with coal through the opening *b*, the coal is lighted, and the opening built up with masonry or fire-brick. When the oven is heated, air is admitted through the valve *h*, and, passing through the pipe *g*, 55 becomes heated, and is finally discharged in unbroken volume through a single orifice into the oven, directly to the center of the opening *e*, acting upon and expediting the carrying off of the gases from the coal, thereby causing the 60 conversion of the latter into coke to take place exactly as desired, and with greatly-increased production of coke, as compared with ordinary coke-ovens.

The condition and temperature of the interior of the oven can be ascertained by observation through the small pipe *i*.

The pipe *g* may be made to pass two or more times round the oven, or it may be made straight, without passing round the latter.

The operation of my device is not confined to coke-ovens circular in plan, but may be applied to ovens rectangular or of other shape in plan, and it may be readily applied to existing ovens.

I am aware that it is old to employ an air-pipe located in the wall of the coke-oven, through which a blast is blown for carrying off the gases from the coal, and that a sight-pipe connected with a blast-pipe is also old.

Having thus described my invention, what I claim, and desire to secure by Letters Patent, is—

The combination, with the oven *a*, having the flue-opening *e*, of the pipe *g*, having an 85 air-regulating valve at one end, and resting upon the furnace or oven with its other end, provided with a pipe, *i*, extending into the oven in line with the flue-opening *e*, and provided at its outer end with the pipe *l*, as and 90 for the purpose set forth.

In testimony whereof I have signed my name to this specification in the presence of two subscribing witnesses.

ARTHUR MARSHALL CHAMBERS.

Witnesses:

JOHN BAKER,
HARRY HUTCHINSON.
